J. F. NEILEY

STAMPING ATTACHMENT FOR HIDE SPLITTERS

Filed April 4, 1921

James F. Neiley INVENTOR.
By Alexander Dowell Attorney.

UNITED STATES PATENT OFFICE.

JEWETT F. NEILEY, OF ENDICOTT, NEW YORK.

STAMPING ATTACHMENT FOR HIDE SPLITTERS.

Application filed April 4, 1921. Serial No. 458,450.

To all whom it may concern:

Be it known that I, JEWETT F. NEILEY, a citizen of the United States, residing at Endicott, in the county of Broome and State of New York, have invented certain new and useful Improvements in Stamping Attachments for Hide Splitters; and I hereby declare that the following is a full, clear, and exact description thereof, reference being had to the accompanying drawings, which form part of this specification.

This invention is a novel stamping mechanism designed for stamping green hides before placing same in the tanning liquors in order to identify the particular kind of hide by the stamp. The invention is especially adapted for connection with hide splitting horses on which the hide is properly cut preparatory to tanning.

The common method of stamping hides is to have a die attached to the head of a hammer-like instrument which is brought down with some force upon the hide and by which the outline of the die will be cut into the surface of the hide usually upon some part of the head end or butt end of the hide. This is done after the green hide is thrown over a "horse" which is something like a saw horse except that instead of having one bar at the top it consists of two bars on the same level separated by a little space.

My present invention is particularly designed for use in connection with such "horses" so as to stamp both halves of the hide simultaneously. I will explain the invention as applied to such a horse, with reference to the accompanying drawings, and summarize in the claims the novel constructions and combination of parts for which protection is desired.

In said drawings;

Fig. 1 is an end view of a hide splitting horse and of my stamping attachment applied thereto;

Fig. 2 is a side view of Fig. 1 showing the attachment in detail.

Fig. 3 is a detail section on the line 3—3 Fig. 2.

A, A designate the parallel top bars of a well known type of hide splitting "horse," which somewhat resembles an ordinary saw horse, these bars being supported by legs B which may be connected at the bottom by a tie rod C and may be fastened to the bars A, A and to each other by through bolts D.

The particular construction of this horse is not a feature of the present invention.

Adjacent one end of the horse and near the end of each bar A, is an inverted L-shaped stamp carrying member having a horizontally disposed head 1, which is provided with a socket on its under side for the reception of a removable stamp or die S which can be secured thereto by a bolt 1^a; the face of the die S projecting below the lower side of the member 1 and normally lying above the top of the bar A. Preferably a lead block 2 is inserted in a recess in the upper side of each bar A below and opposite the die S so as to act as a platen for the die.

The stamp carrying member 1 has a shank portion 1^b which extends through a slot or guide channel in the side of the bar A and is confined therein by a plate 3 which if desired may contain a groove or slot for guiding the shank 1^b. The lower ends of the shanks 1^b of the adjacent stamp members are preferably connected together by a tie 1^c preferably bolted thereto as shown, and the stamp members are normally held in elevated position by any suitable means, preferably by contractile helical springs 4 attached to the underside of the bars A, A and to the tie 1^c.

To the tie 1^c is connected a bolt 5 which is adjustably secured thereto by nuts 5^a; and said bolt is connected by links 5^b to a bell crank treadle, which has a short arm 6^a pivotally connected at 6^b to a bracket 7 fastened to the underside of the bars A, A and reinforced by a brace 7^b, see Fig. 2. The longer arm 6 of the treadle is guided between vertical bars 8 attached to the bottom tie C and at the top to legs B as indicated in Fig. 1.

In the construction shown the stamp carrying members and the treadle 6 are normally held in elevated position by action of the springs 4.

Obviously changes may be made in the particular construction of the parts of the device while retaining the essential and novel features of invention. I therefore do not consider the invention restricted to the specific embodiments thereof shown in the drawing.

Operation: A green hide is thrown over the horse and the head or butt portion of the hide is inserted under the heads 1 be-

tween the dies S and the blocks 2. Then the operator depresses the treadle 6 with his foot thereby bringing the dies forcibly down upon the hide and impressing the stamps 5 thereon. After the impressions are made upon the hide, and while it rests upon the horse it is usually slit from head to tail by the operator drawing a sharp knife lengthwise between the two top bars of the 10 horse, thus splitting the entire hide into two "sides."

Some of the advantages of my invention are; the stamps can be placed in exactly the same place on each hide; are thoroughly 15 legible; the work is uniform and the stamping is greatly facilitated, as the operator by simply depressing the treadle performs operations that heretofore ordinarily required four operations by hand, to wit, picking up a hammer, striking each side die once with the hammer and then laying down the hammer. The treadle and dies are automatically returned to original position by the springs when the treadle is released. 20 25 The device is simple and inexpensive in construction and no special skill is required by the operator.

What I claim is:

1. A hide splitting horse having parallel 30 top bars; a stamping member mounted on each bar adjacent one end thereof; spring means for normally holding the die carrying members in raised position, and means for simultaneously depressing the die carrying members.

2. A hide splitting horse having parallel top bars; a die carrying member slidably mounted on each bar adjacent one end thereof; a die carried by each member; spring 40 means for normally holding the die carrying members in raised position, and a treadle for simultaneously depressing the said members.

3. In combination with a hide splitting 45 horse having parallel bars, a movable die

carrying member for each bar adjacent one end thereof each member having a die carrying portion on its upper end and a shank depending below the bar; a connection between the shanks of the members below the bars, a treadle; a connection between said treadle and said members whereby the said die carrying members may be simultaneously depressed; and means for normally raising the members and treadle. 50 55

4. In combination with a hide splitting horse having parallel bars, a vertically movable die stamping member slidably attached to each bar adjacent one end thereof each member having a die carrying portion on its upper end and a shank depending below the bar; a connection between the shanks of the members below the bars; a treadle pivotally mounted on the horse below the bars; an adjustable connection between said treadle and said die whereby the said die carrying members may be simultaneously depressed, and springs for normally raising the die carrying members and treadle. 60 65

5. For a hide splitting horse having a longitudinal slot for guiding the knife in splitting a hide; an attachment comprising a pair of movable stamping members attached to the horse at opposite sides of the slot; a treadle and connections adapted to 70 75 depress the members; and spring means for normally holding the treadle and members in raised position.

6. A hide splitting horse having parallel top bars; a pair of members mounted on the horse adjacent one end of the bars; devices to operate on the hide carried by said members; spring means for normally holding the members in raised position; and means for simultaneously depressing the said members 80 85 to cause the devices to operate on the hide.

In testimony that I claim the foregoing as my own, I affix my signature.

JEWETT F. NEILEY.
